HEADPHONE EARPIECE

Richard H. Van Den Berg, Glendale, Wis., assignor to
Dimensional Products, Inc., Milwaukee, Wis., a corporation of Wisconsin

Filed Feb. 4, 1963, Ser. No. 73,430

Term of patent 14 years

(Cl. D26—14)

Fig. 1

Fig. 2

Fig. 3

Fig. 4

Fig. 5

FIG. 1 is a side view in elevation of a headphone earpiece, showing my new design,

FIG. 2 is a front view in elevation of the same,

FIG. 3 is a rear view in elevation of the same,

FIG. 4 is a top view of the same; and

FIG. 5 is a view in section of the outside configuration of the headphone earpiece taken on line 5—5 shown in FIG. 3.

In the drawing the stippling represents a simulated leather surface texture.

I claim:

The ornamental design for a headphone earpiece, as shown and described.
